UNITED STATES PATENT OFFICE.

PERCY T. FROST, OF EAST LIVERPOOL, OHIO, ASSIGNOR TO THE SMITH-PHILLIPS CHINA COMPANY, OF EAST LIVERPOOL, OHIO, A CORPORATION OF OHIO.

DESIGN FOR A PLATE OR SIMILAR ARTICLE.

43,923.

Specification for Design.

Patented Apr. 29, 1913.

Application filed July 1, 1912. Serial No. 707,105. Term of patent $3\frac{1}{2}$ years.

To all whom it may concern:

Be it known that I, PERCY T. FROST, a citizen of the United States, residing at East Liverpool, in the county of Columbiana and State of Ohio, have invented a new, original, and ornamental Design for a Plate or Similar Article, of which the following is a specification, reference being had to the accompanying drawing, forming part thereof.

The figure is a plane view of a plate showing my design.

I claim:—

The ornamental design for a plate or similar article, as shown.

PERCY T. FROST.
